SHOE HOLDER

Thomas Crocella, New York, N. Y.

Application July 25, 1933, Serial No. 682,155

8 Claims. (Cl. 12—123)

This invention relates to shoe holding devices, being intended to be used in the making or repairing of shoes.

The invention provides an improved device for embracingly engaging completely around the exterior of and for holding a shoe upper in proper relation to a last so as to facilitate the operation of applying thereto the sole or soles and filling.

More specifically the invention resides in a device of the indicated character which embodies a plurality of relatively movable shoe upper engaging and clamping sections and a common means for simultaneously effecting relative movements of the sections towards and away from each other so that the same may be expeditiously engaged with a shoe upper and held by the device or released therefrom.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

30 In the drawing:

Fig. 1 is a horizontal section taken approximately on line 1—1 of Fig. 2.

Fig. 2 is a view, partly in elevation and partly in section, of the device, this view showing a shoe 35 on one of the lasts.

Fig. 3 is a fragmentary rear elevation of the device.

Fig. 4 is a view showing the lasts proper in section and showing in elevation part of the support for the lasts; and

Fig. 5 is a fragmentary view showing a modification of part of the device of my invention.

Referring to the drawing for a more detailed description thereof, the numerals 7 and 8 indicate blocks which are respectively supported by standards 7a and 8a. Said blocks are movable towards and away from each other by means hereinafter to be described and are recessed to receive the ends and inner sides of shoes placed on lasts 10. The outer sides of the shoes are supported by arms 12 which are in the form of bell crank levers and are movable laterally toward and away from the shoe. The levers 12 are pivoted to the block 7 at 13 and their confronting ends adjacent these pivotal points are arcuate and

toothed and are engaged by a worm 14 formed on a shaft 15 which may be turned by a hand wheel 16. It will readily be understood that the turning of the wheel 16 is effective to move the levers or supports 12 laterally towards or away from the outer sides of the shoes. The shaft 15 is provided with shoulders 17 fitting into corresponding recesses in the block 7, the shaft thereby being held from moving lengthwise of itself. An end of the shaft 15 projects into a recess 28 in the block 8 and threadedly engages said block as indicated by the numeral 19 so that the turning of the wheel 16 is effective to move the block 8 to and away from the block 7, said block being slidably mounted on the support 8a, having a groove 8b which receives the head 8c of the standard 8a. It will thus be seen that the turning of the hand wheel 16 is effective to move the levers 12 towards or away from the shoes and in the same time to move the block 8 towards or away from the block 7. Means are thus provided whereby the shoes may be securely held in position while they are being worked on.

In Fig. 5 I show a block 8d corresponding to the block 8, shown in Figs. 1 to 3, inclusive. The block 8d differs from the block 8 in that it comprises parts 8e having a plurality of apertures 8f, into any of which screws 8g may be secured in order to adjust the member 8e at any desired position relative to the toes of the shoe 21. It will readily be understood that the block 8d may have adjustable side members corresponding to the members 8e to support the inner sides of the shoes and that block 7 may also have members corresponding to the members 8e adjustable to the heels of the shoes.

What is claimed is:

1. A device of the character described, including a pair of clamping sections mounted for relative movement with respect to each other in the direction of the length of a shoe and adapted to engage around the forepart, the inner side and the heel portion of the shoe, a clamping section adapted for relative movement with reference to the first mentioned sections and to engage the outer side of the shoe, and means for effecting relative movement of said clamping sections towards and away from each other and to and from clamping engagement with the shoe upper so as to embracingly engage with the lasted shoe upper and to disengage the same.

2. A device of the character described, including a pair of clamping sections mounted for relative movement with respect to each other in the direction of the length of a shoe and adapted to

engage around the forepart, the inner side and the heel portion of the shoe, a clamping section adapted for relative movement with reference to the first mentioned sections and to engage the outer side of the shoe, and a common means for simultaneously effecting relative movement of said clamping sections towards and away from each other and to and from clamping engagement with the shoe upper so as to embracingly engage with the lasted shoe upper and to disengage the same.

3. A device of the character described, including a pair of clamping sections mounted for relative movement with respect to each other in the direction of the length of a shoe and adapted to engage around the forepart, the inner side and the heel portion of the shoe, a fulcrumed clamping section adapted for relative movement with reference to the first mentioned sections and to engage the outer side of the shoe, and means for effecting relative movement of said clamping sections towards and away from each other and to and from clamping engagement with the shoe upper so as to embracingly engage with the lasted shoe upper and to disengage the same.

4. A device of the character described, including a pair of clamping sections mounted for relative movement with respect to each other in the direction of the length of a shoe and contoured and adapted to engage around the forepart, the inner side and the heel portion of the shoe, a clamping section adapted for relative movement with reference to the first mentioned sections and to engage the outer side of the shoe, and means for effecting relative movement of said clamping sections towards and away from each other and to and from clamping engagement with the shoe upper so as to embracingly engage with the lasted shoe upper and to disengage the same.

40 5. A device of the character described, including a pair of clamping sections mounted for relative movement with respect to each other in the direction of the length of a shoe, elements carried by and contoured so as to adapt the same for intimate engagement with the forepart, the inner

side and heel portion of shoes of various sizes, a clamping section adapted for relative movement with reference to the first mentioned sections and to engage the outer side of the shoe, and means for effecting relative movement of said clamping sections towards and away from each other and to and from clamping engagement with the shoe upper so as to embracingly engage with the lasted shoe upper and to disengage the same.

6. A device of the character set forth, including a plurality of clamping sections contoured and adapted to cooperatively function to embracingly engage completely around the exterior of a lasted shoe upper in the region of the normal lower edge thereof, one of said sections being relatively movable with respect to another in the direction of the length of the shoe and another of said sections being horizontally swingable with respect to said other sections, and means for simultaneously effecting relative movement of said sections towards and away from each other to engaged and disengaged positions with the shoe upper.

7. In a device of the character set forth, blocks adapted to receive the ends and inner sides of a pair of shoes having lasts therein, a pair of laterally movable supports for the outer sides of the shoes, and means for moving said supports laterally towards or away from the outer sides of the shoes and for simultaneously moving said blocks relatively towards or away from each other.

8. In a device of the character set forth, blocks adapted to receive the ends and inner sides of a pair of shoes having lasts therein, a pair of laterally movable supports for the outer sides of the shoes, means for moving said supports laterally towards or away from the outer sides of the shoes and for simultaneously moving said blocks relatively towards or away from each other, said supports being in the form of bell crank levers having toothed arcuate confronting ends and said means including a worm engaged with said teeth of said levers.

THOMAS CROCELLA. 45
